INVENTOR

UNITED STATES PATENT OFFICE

THORMOD JENSEN, OF BROOKLYN, NEW YORK

AUTOMATIC CONTAINER-CAP LINING MACHINE

Application filed September 12, 1929. Serial No. 392,199.

This invention relates to container cap-liner making and inserting machines for automatically cutting out resilient liners of paper, cork, or similar material, for metal, glass, or other container-caps, and inserting the same into the said caps, the object of the present invention being to accomplish the cutting of the liners and their subsequent insertion into the caps at a high rate of speed.

10 Machines at present in use for lining container caps, owing to their single-acting construction, are slow in production their speed limit being 100 to 150 cap-linings per minute. By a double-action arrangement and by other 15 features incorporated in my invention, the present machine can be used for speeds of from 200 to 400 caps per minute, or more, according to the size of the caps and to the material and thickness of the liners.

20 For the purpose of achieving the object of my invention, the present machine has the following parts and arrangement: A continuously driven cap conveyer upon which the caps are placed in spaced relation from a 25 moving feed-belt by an endless transfer chain, and on which they are carried in proper spacing and alignment through the machine; a continuously-driven liner-strip unrolling from a reel of the lining material and moved by a pair of feed-rollers above the 30 cap-conveyer at the same speed as the latter; and a twin punch-and-die head reciprocated by an eccentric above the liner strip, in the same and opposite direction to the latter and with the same linear speed. The twin punches are equipped with plungers which 35 take the cut liners from the punches and insert them into the caps.

The cutting of the liners takes place after 40 the head-moving eccentric disk has completed approximately three-tenths of its forward turn, or three-twentieths of a revolution, in the direction of the liner-strip travel, when the center of the eccentric disk moves 45 approximately parallel with the liner-strip, being then near its position of minimum angular variation and maximum linear displacement. The cutting stroke of the punches is completed during the next one-tenth revolution of the driving eccentric,

whereupon the inserting plungers start their downward stroke, completing the same in about one-fifteenth of a revolution of the eccentric, punches and plungers reversing immediately on reaching the ends of their down-strokes and emerging from the liner strip about one-thirtieth revolution of the eccentric after insertion. The cutting, inserting and withdrawal actions thus occupy approximately $1/10 + 1/15 + 1/30 = 1/5$ of a revolution of the eccentric, during which the cutting-head moves at practically the same speed as the liner strip, namely from about one-tenth of a revolution before its vertical center position to one-tenth of a revolution after this position.

In the present machine, therefore, double production is obtained by a reciprocating twin punch and die, lining two caps simultaneously while moving with the liner-strip. The cap conveyer and the liner strip move at constant speed, and the cutting and inserting operations are performed while motion of the die-head proceeds at that speed, this arrangement resulting in a simple and efficient machine.

In the accompanying drawings:—

Fig. 1 is a side elevation of the new cap lining machine, showing the arrangement of the reciprocating twin-punch and die head, the cap conveyer and the cap timing device, together with the drives for the various moving parts;

Fig. 2 is an end elevation taken on line 2—2 of Fig. 1, showing the punch and die head and its operating means;

Fig. 3 is a top view seen from line 3—3 of Fig. 1, showing the reciprocating means of the die-head and the drives for the liner strip and for the cap conveyer;

Fig. 4 is a top view from line 4—4 of Fig. 1, showing the cap-feed, the cap transfer, timing lever and cap conveyer.

Figs. 5, 6, and 7 are plan view, side-elevation and sectional end elevation, respectively, of the chain used for cap transfer and cap conveyer;

Fig. 8 is a diagram showing the operation of the machine during one complete cycle; and

Figs. 9 to 12 are diagrams showing the position of the die-head and of the punches and inserting plungers in the same, at 0° , 90° , 114° , and 180° , positions of the die-head 5 eccentric, respectively.

Referring to Figs. 1, 2, and 3, the frame 15 of the machine supports the main drive shaft 16, the cam shaft 17, the fulcrum shaft 18, the sprocket shafts 19, 20, 21, 22, 23 and 24, the pulley shaft 25, the feed-roller shafts 26 and 27, the idler shaft 28, the reel shaft 29, and the guide-roller shafts 30 and 31.

Shaft 16 carries a sprocket 32 connected by chain 33 with sprocket 34 on shaft 17. A spur gear 35 mounted on shaft 16 drives the gear 36 on sprocket shaft 19, the gear 36, in turn, meshing with gear 37 on feed roller shaft 26. The latter shaft has the sprocket 38 which, by means of chain 39, drives the sprocket 40 on shaft 23. A sprocket 41 on shaft 19, by means of chain 42, drives the sprocket 43 on shaft 20.

In the bearings 44 of frame 15 are mounted the horizontal shafts 45 on which slides the die-head 46 which is set into reciprocating motion by the eccentric disk 47 on drive shaft 16 through connecting lever 48 pivoted to lug 49 of the die-head. The die-head 46 carries the twin punches 50 into which are fitted the twin plungers 51. The punches 50 are actuated by the eccentric disks 52 mounted on cam shaft 17, their hoops 53 carrying strips 54 in the ends of which the head 55 of the twin punches 50 is pivoted. The plungers 51 are suspended from the lever 56 fulcrumed on shaft 18 by means of the slotted link 57, pivoted to their head 58. The lever 56 carries the roller 59 held in engagement with cam 60 attached to one of the eccentric disks 52 on shaft 17 by a coil spring 61 stretched from pin 62 in lever 56 to pin 63 in frame 15. The shaft 17 passes through the slot of link 56 which slot is made of such size as to clear shaft 17 both in its vertical motion due to cam 60 and in its horizontal motion due to the reciprocation of the die-head.

The bottom of the die-head is recessed so that a shallow slot is formed above the ledger plate 64 which is held against the die-head by the cover-plate 65. Through this slot passes the liner strip S which is drawn off the reel 66 on shaft 29 by the feed-rollers 67 and 68 on shafts 26 and 27, respectively. One of the feed-rollers, 67, is driven from the main shaft 16 by the spur gear 35 meshing with gear 36 on shaft 19, the latter gear, in turn, meshing with gear 37 on shaft 26. The other feed-roller, 68 is held in tension against strip S by springs 69 attached to pins 70 and 71 at the ends of shafts 26 and 27. The strip S is guided into the feed-rollers by the roller 72 on shaft 30, supported by bracket extensions 73 of frame 15, and is led out of the machine by the guide roller 74 on shaft 31.

The cap feed is shown in Figs. 1 and 4. The caps are placed on feed belt 75 which runs over pulley 76 on shaft 25, driven from shaft 22 by sprocket 77, connected by chain 78 with sprocket 79 on shaft 25. Near the end of the feed belt, the caps C are stopped by the projection 80 of timing lever 81 which is fulcrumed on stud 82 and held in tension by a spring 83. A transfer chain 84, running over sprockets 85 and 86 on shafts 23 and 24, respectively, and driven by sprocket 88 on feed-roller shaft 26 through chain 39 and sprocket 40, is provided with two rows of radially projecting taper-ended pins 87 spaced to correspond with the cap-pitch of the die-head. By means of the pins 87 of one row, the chain 84 actuates the timing lever 81 at proper intervals and thereby allows one cap at a time to pass the projection 80. The cap thus admitted is caught by one of the pins 87 of the other row of transfer chain 84 and carried by the same over the bridge-piece 88 onto the conveyer chain 89 on which it drops into spaced position, between two pins 90, similarly placed as pins 87 of chain 84. The conveyer chain 89 runs over the sprockets 91, 92 and 93 on shafts 22, 21, and 20, respectively, being driven by the chain 42 running over sprockets 41 and 43 on shafts 19 and 20, and over idler 94 on shaft 28.

As seen by the plan view in Fig. 4, the feed belt 75 and the conveyer chain 89 are in line, the caps reaching the conveyer chain being each located in position by one pair of pins 90 belonging to the same chain link. The transfer chain 84, on the other hand, is laterally displaced with respect to the feed belt and conveyer chain, one row of its pins 87 coinciding with the center line of the latter while the other row of pins projects over one side of the same. While the centrally located pins of the transfer chain thus are in the proper position to engage the arriving caps, the outer pins are available for the operation of the timing lever, the open position of which, due to the action of one of the pins 87 on its inwardly projecting end 81', is shown in dotted lines in Fig. 4. The feed belt 75 is driven at twice the linear speed of the conveyer chain, so that the caps fed onto the belt quickly reach the transfer point and there is always a plentiful supply of them when the timing lever opens the passage. Side-guides 95 keep the advancing caps in line during their progress on the feed belt and conveyer chain, and supports 96, Fig. 2, between the sprockets 92 and 93 sustain the caps on the conveyer while the liners are being inserted into them.

The construction of the chains used for transferring and conveying the caps is shown in Figs. 5, 6, and 7. The pitch of the chain is so chosen that a whole number of links is required to make up the cap-pitch which is identical with the center distance of the twin punches. In the example shown, this number

is 3, and thus every third link is provided with horizontal extensions 97 to both sides of the chain, these extensions carrying the vertical taper-pointed pins 87 (or 90). Since 5 the number of links per cap-pitch in this case is an odd number, the extensions 97 are alternately carried by outside and inside links, Fig. 6; in case of an even number, all 10 pins would be carried by extensions of outside links.

The operation of the machine is illustrated by the diagram shown in Fig. 8. The beginning of the die-head stroke is designated by 0°, the middle of its forward stroke of 90°, 15 the end of the forward stroke by 180°, and the end of the return stroke which corresponds to one complete revolution of the eccentric disk 47, by 360°. As the liner strip S and the caps C on conveyer chain 89 moves 20 forward, the punches 50 descend until, at about 54°, when the die-head 46 commences to travel at approximately the same linear speed as the strip and the caps, they engage the liner strip, and cutting of the liner commences. At 90°, in the middle of the forward 25 stroke, the punches, after completing the cutting, have reached their lowermost position and begin to withdraw while, at the same time, insertion of the liners L into the caps 30 C by the plungers 51 commences, the inserting stroke being completed at about 114°, whereupon withdrawal of the plungers takes place, the plungers emerging from below the liner strip at about 126° when the linear forward speed of the die-head begins to fall off 35 substantially. The engagement between the liner strip and the punches and plungers in each cycle thus lasts from about 54° to about 126°, or for approximately 72° or one-fifth of 40 a revolution. While the center of the die-head moves at variable speed from *a* to *b*, corresponding to the movement from 0° to 180° of the eccentric, the caps on the conveyer move at uniform speed from the position 45 shown at *d* to that shown at *f*. At the center of the forward stroke, 90°, the die-head, as shown at *c*, is concentric with the caps then in position *e*, and its speed has its maximum value which is identical with the uniform 50 liner and conveyer speed. Between 180° and 360°, the die-head returns from *b* to *a* while the caps continue forward to the position shown at *g*, in which two new caps shown by dotted lines have just entered into starting 55 position under the die-head (corresponding to the position *d* of the old caps) so that the cycle is now repeated.

Figs. 9 to 12 show the position of the die-head, caps, punches, plungers, and punch- 60 and plunger-actuating parts at the beginning of the die-head stroke, or 0°, at the center of the forward stroke, or 90°, at the end of the insertion stroke, or 114°, and at the end of the forward stroke, or 180°, of the die-head eccentric respectively. In Fig. 11, the insert-

ing plungers 51 are in their lowermost position, the roller 59 having descended from its upper to its lower position between 90° and 114° while the cam 60 has advanced by 24°. After a further advance of 12°, the 70 roller will have returned to high position so that at 126° the plungers are again on their normal level above the liner strip.

At 0°, Fig. 9, both punches and inserting plungers are above the liner strip S, so that 75 the latter, which then travels faster than the die-head, is not interfered with by the former. At 90°, Fig. 10, the punches are at the end of their downward stroke, having cut the liners L from the strip S, the cam 60 is at the end of its circular dwell, and the caps C are concentric with the die-head. At 114°, Fig. 11, the cam-roller 59 is down, the liners L are inserted in the caps C which are still concentric with the die-head, as from 54° to 126° the 80 latter has the same linear speed as the conveyer, and the punches 50 have started on their upward stroke. At 180°, Fig. 12, finally, the die-head 46 is in its extreme forward position, ready to begin its return stroke, and the caps C, which have commenced to gain on the die-head at 126°, are now well in advance of the same and continue 85 their forward motion while the die head returns to its starting point. At 360°, the die-head has returned to the position shown in Fig. 9, the cap-conveyer has moved a distance equal to twice the cap-pitch, so that 90 now the next two caps on the conveyer will be operated upon. In this manner, the new twin machine accomplishes twice the work 95 of an ordinary machine running at the same speed. For still greater production, three or more punches may be combined in one die-head in a similar manner.

Having thus described my invention, I make the following claims:

1. In a container-cap-liner making and inserting machine through which travels a continuous liner strip, the combination, with a continuously moving cap-conveyer, of a twin punch and die carried by a reciprocating head, the said head moving with the said cap conveyer and liner strip and at the same speed during a portion of its forward stroke.

2. In a container-cap-liner making and inserting machine, the combination, with a continuously moving cap conveyer, of a reciprocating multiple punch and die-head equipped with cap-inserting plungers, the said head moving with the said cap conveyer and with a continuous liner strip and at the same speed during a portion of its forward stroke.

3. In a container-cap-liner making and inserting machine, in combination: a cap feed belt, including means for timing the caps; and endless cap conveyer, including means for spacing and aligning the caps thereon, and means for advancing the conveyer continuously at a constant speed; means for 125

- feeding a strip of lining material continuously from a supply reel and guiding it above the caps on the conveyer at the same speed as the cap conveyer; and a multiple punch and 5 die-head with liner inserting plungers, including means for reciprocating the said head with and against the liner strip at a speed which is equal to that of the cap conveyer and of the liner strip for at least a 10 portion of its stroke, and means for operating the said liner-cutting punches and the said liner-inserting plungers during that portion of the forward stroke of the reciprocating head when their speed coincides with 15 that of the cap conveyer and liner strip.
4. In a container-cap-liner making and inserting machine provided with means for advancing a continuous liner strip and having a forwardly moving cap conveyer, a multiple 20 punch and die-head with a reciprocating motion so arranged that, during a portion of its forward stroke, its speed is substantially identical with that of the advancing liner strip and cap conveyer.
- 25 5. In a container-cap-liner making and inserting machine provided with means for advancing a continuous liner strip and having a forwardly moving cap conveyer, a multiple punch-and-die-head provided with liner 30 inserting plungers, and means for operating said punches and plungers and for reciprocating said die-head, the said means being so arranged that the operation of the punches and plungers occurs at the time when the die- 35 head moves in the direction of, and at the same speed as, the liner strip and the cap conveyer.
6. In a container-cap-liner making and inserting machine provided with means for 40 causing a continuous liner strip to travel above and at the same speed as a cap conveyer, a multiple punch-and die-head provided with punches and plungers, means for reciprocating said die-head above said liner 45 strip, and means for operating said punches and plungers; the last named means being so arranged that the operation of the punches and plungers occurs at the time when the die-head moves in the direction of, and at the 50 same speed as, the liner strip.
7. In a container-cap-liner making and inserting machine having a continuously moving cap conveyer and liner strip moving means, a plurality of punches aligned in the 55 direction of the cap conveyer and liner strip movement, the said punches being reciprocated as one unit in the said travel direction in such a manner as to skip on their return stroke, a number of caps equal to their own 60 number, so that the already cut portion of the liner strip and the corresponding portion of the conveyer with the caps already lined pass beyond the range of the punch unit, and new cutting on the next forward stroke 65 starts close to the previous cut.
8. In a container-cap-liner making and inserting machine having a continuously moving cap conveyer, means for feeding the caps one by one in spaced relation from an endless feed belt to the said cap conveyer; 70 the said feeding means including a transfer chain and a timing lever, the said transfer chain being provided with two rows of projecting pins, one row operating the said timing lever so as to admit one cap at a time 75 from the said endless feed belt, and the other row receiving the caps and leading them one by one onto the cap conveyer of the machine.
